UNITED STATES PATENT OFFICE.

FREDERICK W. CUMMINGS AND GUSTAVE H. HANNA, OF CLEVELAND, OHIO, ASSIGNEES TO
SANITARY STREET FLUSHING MACHINE COMPANY, OF ST. LOUIS, MISSOURI.

NOZZLE.

No. 873,301.

Specification of Letters Patent.

Patented Dec. 10, 1907.

Application filed February 4, 1907. Serial No. 355,628.

To all whom it may concern:

Be it known that we, FREDERICK W. CUMMINGS and GUSTAVE H. HANNA, citizens of the United States, residing at Cleveland, in 5 the county of Cuyahoga and State of Ohio, have invented certain new and useful Improvements in Nozzles, of which the following is a specification.

This invention is a nozzle for hose pipe or 10 street sprinklers, and is particularly adapted for use for street cleaning or flushing, and has for its object to provide a nozzle from which will flow a wide sheet of water at an angle suitable to spread water over a large 15 area, and in a single plane in such a manner as to be particularly useful for flushing large surfaces such as streets or the like.

The invention is illustrated in the accompanying drawings, in which

20 Figure 1 is a side elevation of the nozzle. Fig. 2 is a section, reduced, on the line 2—2 of Fig. 1. Fig. 3 is an edge view looking in the direction of the arrow *a*, Fig. 1. Fig. 4 is an edge view looking in the direction of the 25 arrow *b*, Fig. 1. Fig. 5 is a perspective. Fig. 6 is a rear end view.

Referring specifically to the drawings, 6 indicates a water supply pipe leading from the water tank or reservoir. This screws 30 onto the nipple 8 of the nozzle, which nipple projects from a shoulder 10 at the rear of the nozzle. The side walls 9 of the body of the nozzle are curved outwardly, or concave on the inside, and in connection with the end 35 walls 7 form an enlarged hollow or chamber 16 therein. The walls 9 are flared or spread laterally and curved toward each other to form a long narrow mouth or slot between the lips 14. One end wall 7 extends at a 40 greater angle from the axis of the nozzle than the other, and the line of the lips 14 is at an angle to the perpendicular from said axis, so that the lateral extension of the discharge slot is greater on one side of the axis than on 45 the other so that the water is spread on one side more than on the other, as will be clearly apparent from Fig. 1. Also, one of the side walls 9 is curved to a greater extent than the other so that the discharge slot is off-set,

whereby it may be placed or brought in close 50 proximity to the surface to be flushed and will discharge at a small angle thereto, to sweep or flush said surface with greater efficiency than would otherwise be the case.

In use, water when admitted through the 55 pipe 6 fills the chamber 16 and the pressure incident to the narrow or reduced mouth causes the water to be discharged in a sheet therefrom, with considerable force, and when the nozzle is disposed adjacent to the 60 surface said surface will be flushed or cleanly swept by the sheet of water, and in street cleaning the refuse will be washed into the gutter instead of being simply sprinkled, as with an ordinary street sprinkler. The de- 65 vice is also of service for use as a lawn sprinkler or for washing windows or buildings. The angle at which the mouth extends is particularly advantageous for use in street work in flushing carts, as by placing the 70 short end of the nozzle toward the cart, at the rear thereof, the flow of water will be delivered laterally and rearwardly in a most efficient direction to flush the street, as the 75 cart travels along.

I claim:

1. A nozzle comprising a body having opposite concave side walls, and end walls of different lengths which diverge at different angles from the axis of the nozzle and on opposite sides thereof, and the side walls of which converge and form therebetween a narrow mouth, which extends obliquely across the axis of the nozzle, from one end wall to the other.

2. A nozzle having opposite concave side walls forming an enlarged chamber, and a long narrow mouth the plane of which is parallel to and offset from the axis of the nozzle toward one of said walls.

In testimony whereof we do affix our signatures, in presence of two witnesses.

FREDERICK W. CUMMINGS.
GUSTAVE H. HANNA.
